(57) **CLAIM**

The ornamental design for mobile adapted to display photographs, as shown and described.

DESCRIPTION

Claimed is a design for mobile adapted to display photographs comprising three interchangeable portions: one or more mobile portions, an arc armature portion and a supporting structure portion.

FIG. 1 is a perspective view of a mobile adapted to display photographs, showing my new design; and,

FIG. 2 is a perspective view showing an alternate embodiment of my new design.

1 Claim, 2 Drawing Sheets

FIG. 1

FIG. 2
